THEODORE VARNEY, OF PITTSBURGH, PENNSYLVANIA, ASSIGNEE TO WESTINGHOUSE ELECTRIC AND MANUFACTURING COMPANY, A CORPORATION OF PENNSYLVANIA.

ANCHOR STRUCTURE FOR OVERHEAD LINES.

1,078,647.

Specification of Letters Patent. Patented Nov. 18, 1913.

Application filed October 18, 1909, Serial No. 522,478.

To all whom it may concern:

Be it known that I, THEODORE VARNEY, a citizen of the United States, and a resident of Pittsburgh, in the county of Allegheny and State of Pennsylvania, have invented a new and useful Improvement in Anchor Structures for Overhead Lines, of which the following is a specification.

My invention relates to overhead structures for electric lines, and it has for its object to provide a simple and durable anchor structure, by which the terminal of a messenger wire or cable, from which a trolley conductor is suspended, may be securely held under very heavy tension and at the same time electrically insulated from its support, for high voltages.

When a catenary type of overhead line structure is employed in the electrification of steam railroads and other multi-track systems, it is of great advantage to reduce the number of necessary supports by placing them at relatively long distances apart, making each of them particularly rigid and permanent. Under these conditions, the messenger wires or cables from which the trolley conductors are suspended are subject to very heavy strains on account of their own weight and the weight of the trolley conductors between supports. At intermediate supporting structures, the lateral strains are largely equalized so that it is only necessary to sustain a downward pressure, but, at the end of the line section, it is necessary to provide an anchor structure to which the messenger cable may be rigidly secured. Since the messenger cables are electrically connected to the trolley conductors and serve as feeder conductors, it is also necessary to electrically separate the messenger cables from the anchor structure, and, as relatively high voltages are frequently employed in the service above indicated, the requirements for the anchor structure are particularly severe.

According to my present invention, I provide an anchor structure having such an arrangement that tremendous mechanical strains may be sustained and, at the same time, the cables are electrically separated from the support by insulators which are capable of sustaining very high voltages.

Figure 1 of the accompanying drawings is an elevation of an anchor strain terminal constructed in accordance with my inven-

tion, and Fig. 2 is a partially sectional elevation on line II—II of Fig. 1, a portion of the structure being omitted.

Referring to the drawings, the structure here shown comprises a horizontal beam 1, preferably of T-section, which is pivotally secured at its inner end to a relatively heavy cross beam 2 and projects outwardly therefrom. A pair of braces 3 and 4 which are bolted together and to the outer extremity 60 of the beam 1 and are separated at their inner ends and are secured to the cross beam 2 at some distance above the point of connection between the beams 1 and 2. A sheet metal plate 5 is preferably secured to the 65 braces 3 and 4 and constitutes a roof or shed for the protection of the parts below it. A clevis bracket 6 is clamped to the T-beam 1 by means of bolts 7 and it rotatably supports an insulator 8 which is mounted in 70 hooked projections 9 on the clevis. A hanger rod 10 depends from the insulator 8 and a messenger wire or cable 11 is secured to the hanger rod by means of a clamp 12, the end of the messenger wire being 75 connected to the outer end of the structure composed of beams 1, 3 and 4 through a turn buckle 13 and a strain insulator 14. A trolley conductor 15 may be secured to the messenger wire or cable by any suitable 80 means (not shown).

I claim as my invention:

1. An anchor structure for electric lines comprising a substantially horizontal arm or bracket, a clamp pivotally suspended and 90 electrically insulated from said arm or bracket, a wire or cable grasped by said clamp and disposed substantially in the central vertical plane of the arm or bracket, and insulating and tension-adjusting means 95 interposed between the end of the wire or cable and the end of the arm or bracket.

2. An anchor structure comprising a substantially horizontal arm or bracket, a clevis adjustably secured thereto, an insulated clamp pivotally suspended by the clevis, a wire or cable grasped by the clamp and disposed substantially in the central vertical plane of the arm or bracket, and a strain insulator and turn buckle interposed 100 between the end of the wire or cable and the end of the arm or bracket.

3. An anchor structure comprising a bracket which consists of a horizontal beam 110 and a pair of angularly disposed braces the

respective ends of which are secured to one end of the beam and to a vertical supporting wall, a clevis bracket adjustably secured to the horizontal beam, an insulated clamp 5 pivotally mounted in the clevis bracket, a wire or cable secured in the clamp and disposed substantially in the vertical plane of the horizontal beam, and a strain insulator and turn buckle interposed between the end

of the wire or cable and the free end of the 10 bracket.

In testimony whereof, I have hereunto subscribed my name this 4th day of October, 1909.

THEODORE VARNEY.
